UNITED STATES PATENT OFFICE.

OSCAR KLINKE, OF ATTLEBORO, MASSACHUSETTS, ASSIGNOR TO SMITH & CROSBY, A COPARTNERSHIP COMPOSED OF ALFRED D. CROSBY AND GEORGE H. CROSBY, OF ATTLEBORO, MASSACHUSETTS.

DESIGN FOR A BRACELET CHAIN.

Application filed April 14, 1926. Serial No. 17,290. Term of patent 7 years.

To all whom it may concern:

Be it known that I, OSCAR KLINKE, a citizen of the United States, residing at Attleboro, in the county of Bristol, State of Massachusetts, have invented a new, original, and ornamental Design for Bracelet Chain, of which the following is a specification, reference being had to the accompanying drawing, forming part thereof.

The figure of the drawing shows a section of the bracelet chain, the balance of the chain being a mere repeat.

I claim:

The ornamental design for a bracelet chain as shown.

OSCAR KLINKE.
